UNITED STATES PATENT OFFICE.

ACHILLE COUSOT, OF GENEVA, SWITZERLAND.

TOOL-HOLDER.

1,080,422.

Specification of Letters Patent.

Patented Dec. 2, 1913.

Application filed April 25, 1913. Serial No. 763,655.

To all whom it may concern:

Be it known that I, ACHILLE COUSOT, a citizen of the Swiss Confederacy, and resident of Geneva, Switzerland, have invented 5 certain new and useful Improvements in Tool-Holders, of which the following is a specification.

The present invention relates to a device for firmly maintaining in their holders helical metal turning tools taken in the bar of the class described in the application, No. 671,436, filed January 16, 1912, and the improvements consist in the arrangement of the various parts maintaining the tool with 10 in the holder, viz: The packing piece is interposed between the tool and the clamping screw, the lower slotted portion of the tool holder on which portion bears the tool is removed from its holder and the special arrangement of its spring for readily moving 15 or replacing said packing piece.

The invention is shown in the accompanying drawing, in which:

Figure 1 is a vertical section of the tool holder showing the tool and the various clamping devices for maintaining said tool. Fig. 2 is a similar section of the tool holder provided with a spring, all remaining parts being removed. Fig. 3 is a side view of 20 the packing piece. Fig. 4 is a section on line A—B of Fig. 3.

The tool 1, is engaged in a holder *h*, and secured in position by means of a clamping screw *v*, bearing against the packing piece *a*, which is under the action of a spring *m*. 25

The packing piece is trapezoidal and provided with a semi-circular, projecting lug *b*. Said lug *b*, is located in a corresponding groove *b'*, provided in the body of the tool holder *h*, and works as a hinge and prevents the forward sliding motion of the packing piece when the tool is removed from the holder. The front face *o*, of the packing piece *a*, may be inclined so that the cuttings 30 may freely roll up, but this feature is not useful in all cases, and said front face *o*, may be straight. The lower portion of the packing piece *a*, is slightly curved at *c*, in order to provide a convenient resiliency and 35 prevent the screw *v* from becoming damaged when the workman operates same too suddenly.

The two lower surfaces *e* and *d* of the packing piece *a*, are worked so as to fit 40 exactly the corresponding surfaces of the tool, in order to provide a positive clamp-

ing over a large surface. The tool holder is provided with an arc-shaped hollow *h*, so that two clamping surfaces *f* and *g* having the shape of the tool are provided in front of the clamping surfaces *e* and *d* of the packing piece *a*. The last piece is also provided with a slot *n* (Figs. 1, 3 and 4) extending from the upper rear portion of the projection *b* to the lower arc-shaped portion *c*. The depth of said slot *n* (Fig. 4) is such that the spring *m* slides without difficulty alongside the inclined portion of the slot. The packing piece *a* is withdrawn, the spring *m* strikes the lower front of each of the grooves *b'*, as shown in Fig. 2, so that the end of said spring is free. The packing piece *a* (Fig. 3) is ready for being slid into the tool holder. When introducing the packing piece, the inclined edge 75 of the slot *n*, bears against the free end of the spring *m* and said piece may readily slide in the desired position shown in Fig. 1.

Having now fully described my said invention, what I claim and desire to secure by Letters Patent, is:

1. A device for removably securing in its holder a metal turning tool, comprising a centrally slotted tool holder, a tool engaged in the slot of said holder, a hollow at one end of said holder and opening in the central slot of same, a removable packing piece fitting said hollow, means provided at said packing piece and said holder for hingedly and resiliently connecting said packing piece 85 with said tool holder, and means for firmly maintaining said tool between said packing piece and said holder.

2. A device for removably securing in its holder a metal turning tool, comprising a centrally slotted tool holder, a trapezoidal hollow at one end of said holder and opening in the central slot of said holder, a removable trapezoidal packing piece fitting said hollow, a semi-circular projecting lug at 100 one of the upper edges of said packing piece, a correspondingly shaped groove provided on said holder for receiving said lug, a threaded bore on said holder and opening in said trapezoidal hollow, a clamping screw 105 engaging said bore and bearing against said packing piece, arc-shaped hollows provided at the lower surface of said packing piece and at the slotted surface of said holder, ground out surfaces on both sides of each 110 of said arc-shaped hollows for exactly fitting and pressing the adjacent portions of

said tool when the clamping screw is operated, a triangular slot at one side of the near end of said trapezoidal packing piece, and a spring secured on said holder and 5 bearing against the edge of said triangular slot, in order to maintain said packing piece when the tool is removed from its holder.

In testimony whereof I have hereunto set my hand in presence of two witnesses.

ACHILLE COUSOT.
